PREPARATION OF ORTHOPEDIC
APPLIANCES

Salvatore Covino, Medford, Mass.

Application August 10, 1950, Serial No. 178,733

6 Claims. (Cl. 18—55.05)

1

My invention relates to the preparation of orthopedic appliances and particularly to molded arch and foot supports of the type which are inserted in the shoe as separate members. Although useful for the relief of divers foot troubles, I have found that my novel process of preparing foot supports makes possible the production, for the first time, of a support capable of relieving distress occasioned by heel spurs.

While conventionally prepared orthopedic supports have been found generally satisfactory for the treatment of fallen arches and the like, it has evidently not previously been possible to provide a satisfactory cushion or support capable of increasing the walking comfort of those persons afflicted with spurs; i. e. bony outgrowths from the heel bone.

The most important object of my invention is to improve the quality, efficiency and range of use of orthopedic supports.

Another object of my invention is to produce an orthopedic support conformed not only to the peculiarities of contour of the wearer's foot but also molded accurately to fit the contour of the foot-supporting surface of a shoe already worn or "broken in" by the subject or wearer.

The most important feature of the invention resides in making a male mold presenting the contour of the bottom of the foot, a female impression of the foot supporting surface of the wearer's shoe, and, finally, a resilient pad molded between the foot mold and the shoe impression so that it will conform on its lower surface to the contours of the shoe and on its upper surface to the contour of the foot.

The objects and features of my invention will be more readily understood and appreciated from the following detailed description of a preferred embodiment thereof, selected for purposes of illustration and shown in the accompanying drawings in which:

Fig. 1 is a view in elevation illustrating the step of taking the impression of the subject's foot,

Fig. 2 is a plan view of a mold having the impression of the foot,

Fig. 3 is a plan view of a male mold cast from the impression,

Fig. 4 is a view in cross section along the line 4—4 of Fig. 2,

Fig. 5 is a view in longitudinal section along the line 5—5 of Fig. 2,

Fig. 6 is a view in longitudinal section through the impression, showing the male mold,

Figs. 7 and 8 are views in cross section along the lines 7—7 and 8—8 of Fig. 3,

2

Fig. 9 is a view in perspective through a shoe, portions being broken away, showing the process of forming a mold of the foot supporting surface of the shoe,

5 Fig. 10 is a plan view of a female impression made from the shoe mold,

Fig. 11 is a view in perspective of the male shoe mold,

10 Fig. 12 is a view in longitudinal cross section through the female shoe impression with the male foot impression and process of forming the orthopedic support,

Fig. 13 is a plan view of the resulting molded orthopedic support,

15 Fig. 14 is a view in cross section along the line 14—14 of Fig. 13, and

Fig. 15 is a view in longitudinal cross section through the finished support.

The first step in carrying out the process of 20 my invention is to take a female impression of the foot of the subject or patient. To this end I provide a stool 10 having an integral extension 12 adapted to support the thigh of a patient seated on the stool. I have found that a satisfactory impression cannot be taken if the full weight of the body and thigh is directed against the material of which the impression is made. The optimum condition is that the foot should be partially relaxed, neither carrying the full weight nor being freely suspended.

25 To secure the desired impression I provide a box 14 having in its bottom a fairly thick layer 16 of cotton batting, sponge rubber or the like, on which rests an inner box 18 containing a quantity of wet plaster of Paris 20. By supporting the thigh of the subject and providing the resilient base 16 for the container for the plaster of Paris I am able to secure the proper pressure on the foot upon the plastic plaster of Paris. After 30 the impression has been taken, the plaster of Paris is permitted to dry hard to form a block 22 containing the female foot impression 24. A

35 thumb tack 26 is inserted centrally in the heel portion of the impression and two other thumb tacks 28 are inserted in spaced relation at either 40 side of the impression adjacent the ball line of the foot.

45 I next spread vaseline or other lubricant upon the surface of the female foot impression and then fill the cavity of the impression with wet plaster of Paris which hardens into a male mold 30 reproducing the contour of the bottom of the subject's foot. In the lower surface of this male mold 30 there will be found impressions 26' and 50 28' from the thumb tacks 26 and 28 which were 55

in the female impression. I next insert three finish nails 32 into the male mold in the centers of the impressions made by the heads of the thumb tacks. The nails are driven in from the bottom of the mold and are left with about $\frac{1}{8}$ " of the head end exposed, it being my purpose to provide spacers which hold the lower surface of the male mold about $\frac{1}{8}$ " or $\frac{1}{4}$ " from any surface upon which it may be placed.

The next step in carrying out the process of the invention is to provide a female impression of the foot-supporting surface of a shoe which may or may not have been worn or "broken in" by the subject. After a shoe has been worn by one person for a time, it has imparted to it a characteristic contour as the material, particularly the bottom filler, flows in response to pressures exerted by the subject when walking. To secure the desired impressions I first line the interior of the shoe 34 with a layer 33 of paper over which is placed a layer 38 of cellophane or other thin flexible material. Into the lined shoe I introduce a mass of wet plaster of Paris which is allowed partially to dry and is then pressed with the fingers or with a suitable implement so that it will flow sufficiently to take on the exact contour of the foot supporting surface of the shoe 34. The plaster of Paris mold 40 is shown in perspective in Fig. 11.

I next provide a rectangular container 42 filled with fluid plaster of Paris and press it into the male mold 40, after the latter has been greased to prevent adhesion. The mold 40 is pressed into the plaster of Paris in the container 42 to provide a female impression reproducing exactly the contour of the mold 40, in other words the contour of the foot-supporting surface of the shoe 34. The female impression appears at 44 in Figs. 10 and 12.

After the female impression 44 has been permitted to harden, I fit into it the male foot mold 38 during which operation the protruding nails 32 make three small holes in the bottom surface of the impression 44. After these holes have been thus located, I drive thumb tacks 46 on the centers thus joined. Then I spread in the female shoe impression 44 a layer of a thermosetting resilient plastic material. Although there are many compositions which will be found satisfactory for the purpose, I have achieved considerable success with a composition of sawdust, latex, and glue, the sawdust providing a body and the latex providing the requisite resiliency, while the glue serves as a binder. This composition is initially plastic but becomes stiff and somewhat resilient when heated. I next place the male foot mold 38 into the cavity of the female shoe impression 44 and superpose a pressure plate 50 by means of which uniform pressure is exerted on the upper surface of the mold 38. Pressure is slowly applied so that the mold 38 sinks into the cavity and conforms the thermosetting plastic material 48. Pressure is continued until the nails 32 come to rest on the heads of the thumb tacks 46, thus spacing the bottom of the foot mold 38 an average distance of about an $\frac{1}{8}$ " from the upper surface of the female shoe impression 44, the thickness of the plastic material 48 of course varying as it follows the contours of the mold members.

After the pressing operation has been accomplished the molds are separated and the thermosetting plastic piece 48 is removed and baked to set it in final form. Subsequently the member 48 is provided with a cover 52 of leather or other suitable flexible sheet material.

The orthopedic support thus produced by the novel process of my invention faithfully reproduces on its upper surface every angle and contour of the bottom of the foot of the patient or subject and on its lower surface similarly reproduces the contour of the patient's shoe. When a support of this character is placed in the shoe, the composite foot supporting surface is tailor-made to accommodate the peculiarities of the subject's foot, the support is not only effective to provide a suitably contoured surface but is also a cushion serving to protect the foot against painful impact.

Having thus disclosed my invention and described in detail an illustrative embodiment thereof, I claim as new and desire to secure by Letters Patent:

1. The process of preparing an orthopedic support, comprising the steps of taking an impression of the bottom of the subject's foot, casting a male foot mold from said impression, making a male shoe mold of the inner surface of a shoe worn by the subject, taking an impression of the said male shoe mold, spreading a plastic substance upon the said impression, and pressing the male foot mold into the said impression a predetermined distance to conform said plastic substance to a final shape reproducing on its lower surface the contour of the subject's shoe and on its upper surface the contour of the bottom of the subject's foot.

2. The process of preparing an orthopedic support, comprising the steps of making a female impression reproducing the contour of the foot-supporting portion of a shoe worn by the subject, making a male foot mold reproducing the contour of the bottom of the subject's foot, introducing a plastic mass in said impression, and pressing the said male foot mold into said impression to conform the plastic mass to a support having a final shape in which its lower surface reproduces the contour of the subject's shoe, and the upper surface reproduces the contour of the bottom of the subject's foot.

3. The process defined in claim 2 wherein the plastic material is thermosetting, and wherein the support is removed from the impression and heated to set its shape.

4. The process of preparing an orthopedic support, comprising taking an impression of the bottom of the subject's foot, casting a male foot mold from said impression, making a shoe mold of the foot-supporting surface of a shoe worn by the subject, making a female impression from the male shoe mold, placing a mass of thermosetting resilient plastic material in said impression of the shoe, pressing the male foot mold into said impression a predetermined gauged distance to conform said plastic mass, removing and heating the plastic mass to stabilize its shape, and then covering the set plastic with flexible sheet material.

5. The process defined in claim 4 wherein a plurality of spacers are interposed between the shoe impression and the male foot mold to limit the entrance of the mold into the impression.

6. The process of making an orthopedic support which is characterized by the steps of first reproducing in a foot impression the contour of the subject's foot while the foot is partially relaxed by support of the thigh, then making a male foot mold from the said impression, inserting projecting spacers in the bottom of said foot mold, then reproducing the inner bottom contour of a shoe worn by the subject in a rigid

shoe mold, filling the said shoe mold with a thermosetting plastic material, pressing the male foot mold into said plastic material until the spacers contact the bottom of shoe mold thereby forming a support of predetermined thickness conforming in its lower surface to the contour of the subject's shoe and in its upper surface to the contour of the subject's foot.
